WALL TILE

Arthur R. Dixon, Rowayton, Conn., assignor to
 National Kellastone Company, New York,
 N. Y., a corporation of Delaware

Application September 5, 1931, Serial No. 561,470

12 Claims. (Cl. 72—41)

This invention, relating, as indicated, to a wall tile is more particularly directed to the provision of a tile which when incorporated in a protective wall will form an interior duct that will always be accessible for any subsequent wiring operation.

In large office buildings a serious problem has presented itself in connection with adequately wiring the walls of such buildings so that a large expense need not be incurred if the interior of the building be rearranged. For instance, when a building is first constructed knowledge of original and subsequent tenant requirements for electrical distribution are unknown. Thus it has been necessary heretofore to provide wall and column outlets of far greater number than will be required, but this practice is followed in order to be sure that sufficient outlets will be available as near as possible to the locations desired by the tenant. When such facilities are not provided or if they are inadequate, the building owner is put to the expense of seriously defacing the walls of the building according to the original tenant's requirements for wiring and to follow the same procedure for subsequent occupants of the space. This is especially true where terra cotta tile is used, or other materials of ceramic substance and it is to be noted that such materials are called for by the underwriters and most municipal building codes for the greater portion of the wall surface.

In order to avoid the above disadvantages I contemplate the provision of a corner tile of magnesite composition, which can be drilled, sawed or otherwise operated upon with ordinary carpenter tools. This tile may be set at diagonal corners of the vertical corners of a column of a building, and thus provide access at any future date and at any height on all four sides of the column regardless of the number of partitions which abut the columns.

As another aspect of my invention I contemplate the use of a tile of the same material suitable for incorporation in an ordinary partition wall.

It is also within the objects of this invention to provide a tile which may be used in column construction and placed centrally of such columns where building codes permit such construction.

In the following description I will refer to my novel wall tiles as magnesite tiles because of their composition, but this reference is not intended to be limiting, as tiles of other materials may be used which have the same characteristics, namely, the ability to be sawed, drilled and otherwise worked with ordinary carpenter tools. The term "magnesite tile" is used merely to distinguish my tile from other tiles shown in conjunction therewith.

To the accomplishment of the foregoing and

related ends, said invention, then, consists of the means hereinafter fully described and particularly pointed out in the claims; the annexed drawings and the following description setting forth in detail certain structure embodying the invention, such disclosed means constituting, however, but one of various structural forms in which the principle of the invention may be used.

In the accompanying drawings:—

Fig. 1 is a horizontal sectional view showing my improved tile used with conventional terra cotta tiles and blocks; Fig. 2 is a perspective view of a corner of the column shown in Fig. 1; Fig. 3 is a perspective view of my improved corner tile; Fig. 4 is a modification of the wall of Fig. 1; Fig. 5 is a sectional view of the wall shown in Fig. 4 surrounding a supporting member; Fig. 6 is a perspective view of a partition wall; Fig. 7 is a sectional view on line 7—7 of Fig. 6; Fig. 8 is a sectional view on line 8—8 of Fig. 6; and Fig. 9 is a horizontal section showing a modification of the tile and wall shown in Fig. 1.

Referring now to the drawings and more particularly to Fig. 1, it will be seen that a supporting member 1 is illustrated which in this instance has the form of an I-beam, but of course the invention contemplates providing a wall which may surround any preferred form of supporting means. For instance, instead of the I-beam 1 there may be an H-beam, or in some buildings a rectangular or square member, and in some cases, circular columns of metal or other structural supporting materials may be surrounded by my improved wall.

The I-beam 1 must be protected by a fire-proof wall according to the building codes of most cities and this is done by erecting a wall of terra cotta blocks about such I-beam. However, it is well known that terra cotta blocks are almost impossible to drill as their brittle qualities cause them to split. In order to cure this defect I surround the I-beam 1 with a series of blocks 2 which for the most part extend in one vertical plane, that is, the four walls surrounding the column have the major portion of their extent in one vertical plane. At one corner of the I-beam the flange 3 has blocks 4 and 5 in close engagement therewith and out of the vertical plane of the blocks 2. A corner block is then placed in the wall so that a body portion 6 extends flush with the outer surface of the blocks 2, and a body portion 7 extends similarly with respect to the blocks 2, but at right angles to the first-named blocks. The end of the body portion 6 has a web 8 which in this instance extends obliquely from the body portion 6 in order that the mortar may act to tie in the corner tile. The body portion 7 is longer than the body portion 6 and has a web 9 which is spaced from the end 10. The web 9 extends approximately

at the same angle as the web 8 so that the blocks may be molded with least difficulty, but it will be seen that the web may obviously extend at practically any desired angle for various jobs.

5 At the corner opposite to that just described, there is another block built into the wall in exactly the same manner and it will be seen that the diagonal relationship will provide ducts which are sufficient for all practical purposes 10 as the partitions are usually run to the center of the column. I do not desire to limit myself, however, to this specific showing, and may use corner tiles as described, in each of the corners of the column.

15 In Fig. 2 the method of assembling the wall is clearly shown in which terra cotta tiles 2 are illustrated having staggered vertical joints. The staggering of the vertical joints aids in bonding and tying the corner tile to the wall, the corner 20 tiles having their body portions 6 and 7 reversed with respect to each other as the wall proceeds upwardly. This is made possible by the provision of the webs 8 and 9 in the manner described. Each of the wall tiles has a length equal to a 25 conventional terra cotta block plus a mortar joint, and this is done in order that no mortar be used between the horizontal joints. If such mortar were used a large portion of it would fall into the duct and choke up such duct. A further means of bonding the corner tiles is provided in small exterior recesses 11 and 12 which may have a slight amount of mortar trowelled in flush with the exterior face of the tile. This recess will not extend to the interior surface of 30 the tile and thus the duct will be kept clear from top to bottom.

The construction shown in Fig. 2 is illustrated as being supported upon base tiles 13 and 14 in which there are illustrated race-ways 15 and 40 16, and it will be seen that wires may be led along these race-ways and carried up through openings 17, 18 and 19, and thus into the vertical duct 20. My invention however, does not depend upon the use of such specific base tile 45 and may be used with any other form of base board construction. After the structural members of the column are erected, the whole wall receives a coating of plaster 21, after which a base board 22 is applied and the wall is completed. From this it will be seen that no wiring 50 will have to be installed, switch boxes, plates or receptacles installed until such time as the occupants of the space will require these facilities. Whenever outlets are required, such operations 55 may be accomplished by merely drilling the corner tiles with an ordinary brace and bit and then fishing the wires through that hole and down to the base tile or other connecting points.

In the modification shown in Figs. 4 and 5 I 60 have provided a flat tile 36 to be used at locations other than a corner of the column. This tile 36 has an end web 37 and another web 38, said webs acting as spacers and accurately aligning the magnesite tile with the terra cotta blocks 39. The terra cotta wall 39 surrounds an I-beam 65 40 and closely abuts the end flanges 41 and 42 on such I-beam. In the center of the walls of terra cotta there is an inner wall composed of blocks 43 and 49 which back up the magnesite block 36. This construction, while losing some of the flexibility shown in Figs. 1 and 2, is cheaper in total cost as it saves $1\frac{1}{2}$ inches in the exterior size of the column as compared to the constructions shown in Figs. 1 and 2. It is also less expensive to construct because the flat tiles

36 will be cheaper to manufacture than the corner tiles above referred to. The flat tile 36 will form a duct 43 which, because of its width, should be accessible even in the event that a partition is erected which centrally abuts the 5 column. Another duct 44 is formed but this extends only the length of one block due to the vertical staggering of the joints. These blocks may also have small recesses 45 and 46 which will receive mortar and thus act to bond the 10 wall.

Under ordinary circumstances this wall will be covered with a plaster coat 46, after which the base board 47 will be secured to the wall thus completed. The wires will be led into the duct 15 43 in the same manner as described in connection with the corner tile and obviously outlets and fixtures may be applied to the wall at any height and at any subsequent date without any injury whatsoever to the wall and in a much 20 shorter time.

In the modification shown in Figs. 6, 7 and 8, a magnesite partition tile 56 is illustrated incorporated in a partition wall completed gradually of units 57 of ceramic material. In this instance, 25 these ceramic units will be terra cotta blocks but obviously cinder, gypsum or concrete blocks may be used just as well. Magnesite tile 56 has a width corresponding to that of the ceramic tiles 57 and will also have interior chambers 60 and 61, and 30 an open end chamber 62.

By an inspection of the sectional views shown in Figs. 7 and 8, it will be seen that the interior chambers 60 and 61 are continuous and form two vertical ducts, whereas the end chamber overlies a terra cotta tile of the next succeeding subjacent course. As illustrated, these tiles are shown supported by a base block 63 having channels or race-ways 64 and 65. These channels are for the reception of high and low tension 40 wires and such wires may be easily led into the duct formed by the chambers 60 and 61 by merely removing the base board 66.

In the modification shown in Fig. 9, I have 45 shown a structural supporting member which, in this instance, is an I-beam 67 which is surrounded by a wall of terra cotta block 68 except at the corners. A special tile is shown at the corners and this tile is a modification of the corner tile illustrated in Fig. 3. This tile comprises a magnesite corner tile having two body portions 69 and 70, and two end webs 71 and 72. A second corner tile of ceramic material has two body portions 73 and 74 and end webs 75 and 76, the webs of the ceramic tile being cemented or otherwise 55 secured by means of the layers 77 and 78 of adhesive material, to the end webs 71 and 72. This block will be assembled and sold as a unit and while affording the same protection as a complete wall of terra cotta units yet will have the 60 decided advantages of providing a corner duct 79 of considerable volume. Where building regulations permit, this block may be incorporated in a conventional hollow tile wall and will achieve 65 as a result of such incorporation a wall which thoroughly fire proofs the supporting member, and one which may be drilled without injury to the exterior wall at any subsequent time.

From the preceding description it will be seen 70 that I have provided a construction which allows flexibility as well as least expense where walls may be desired to be altered for the provision of electrical outlets. It will also be noted that my improved tile may be incorporated in the wall 75 when such wall is initially built and that a great

saving will result from this for the reason that the building will not have to install a number of outlets which may never be used. It will also be seen that a wall constructed according to my invention may have a fixture and outlet applied thereto without defacing the wall, also the magnesite tile will readily receive wood screws and hold them firmly, thus permitting, with the least amount of labor, the attachment to the wall of outlet plates, fan brackets, electric clocks, telegraph messenger call boxes, etc., at any desired height.

It is also to be noted that the invention will be especially applicable to business offices which make great use of adding machines, annunciators, call systems, telephones, or other means of communication in which wires act as the medium of conduction.

While general construction practice employs terra cotta blocks for fire-proofing interior columns, in some sections of the contrivance wire mesh is wrapped around the steel column and a form set up of wood into which is poured concrete, thus fireproofing the column with concrete. In such cases either the corner column unit or the side column unit could be nailed in proper position on the inside of the form and have nailed on at the back a sheet of asbestos wall board, which installation would keep the raceway clear and concrete could be poured around it, leaving the column unit imbedded in the concrete with its exterior face flush with the balance of the cement column and the whole would then be plastered.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:—

1. A corner tile comprising two body portions extending at angles to each other, said portions having spacing webs extending therefrom, one of said webs extending from an end of one of said body portions and the other web being spaced inwardly from the end of said other body portion, the spacing webs being located equidistantly from the intersection of said body portions.

2. A corner tile comprising two body portions extending at angles to each other, said portions having spacing webs extending therefrom, one of said webs extending from an end of one of said body portions and the other web being spaced inwardly from the end of said other body portion, said tile being composed of a drillable, sawable material.

3. In a column construction, the combination of a supporting member, a terra cotta wall completely surrounding said member, and a series of drillable, sawable and threadable duct tiles associated with said terra cotta wall at a corner of said column, and forming registering openings for substantially the full height of the column.

4. In a column construction, the combination of a supporting member, a terra cotta wall completely surrounding said member, and a series of drillable, sawable and threadable duct tiles associated with said terra cotta wall at a corner of said column, said terra cotta wall being offset inwardly at said corner and said duct tile lying

flush with the exterior thereof, and forming registering openings for substantially the full height of the column.

5. In a column construction, the combination of a supporting member, a terra cotta wall completely surrounding said member, and a series of drillable, sawable and threadable duct tiles associated with said terra cotta wall at a corner of said column, said duct tiles each having a height equal to that of the units of said terra cotta wall plus a mortar joint and having bonding means on top and bottom edges located equidistantly from the corner.

6. A corner tile, adapted to be used in a column enclosure with terra cotta tiles, comprising two body portions extending at angles to each other, said portions having spacing webs extending therefrom, one of said webs extending from an end of one of said body portions and the other web being spaced inwardly from the end of said other body portion, said tile being composed of a drillable, sawable material, and having a height equal to that of a terra cotta tile plus a mortar joint.

7. In a column, the combination of a supporting member, a protective wall of units of ceramic material completely surrounding said member, and a vertical tier of corner tiles associated with said wall in staggered relation, said corner tiles being of drillable sawable and threadable material, and having body portions extending at right angles, one of said portions being longer than the other, and spacing means on said tiles for forming a duct between said units and said tiles.

8. In a column, the combination of a supporting member, a protective wall of units of ceramic material surrounding said member, and a tier of corner tiles associated with said wall, said corner tiles being of drillable material, and having body portions extending at right angles, one of said portions being longer than the other, and said tier having said corner tiles arranged alternately with one of said longer portions adjacent a shorter body portion.

9. In a column construction, the combination of a supporting member having a web and flanges, a wall of terra cotta blocks surrounding said member, central portions of said wall adjacent said web being inwardly offset and a composition duct tile being received in such offset, said composition tile having a height equal to that of one of said terra cotta blocks plus a mortar joint.

10. In a column construction, the combination of a supporting member having a web and flanges, a terra cotta wall surrounding said member, central portions of said wall adjacent said web being inwardly offset and a composition duct tile being received in such offset, the vertical joints in said column being staggered.

11. A corner tile comprising an L shaped, drillable composition tile having webs on its ends, and an L shaped tile of ceramic material having webs on its ends, the webs on each of the ends of said tiles being secured together.

12. A corner tile comprising an L shaped, drillable composition tile having webs on its ends, and an L shaped tile of ceramic material having webs on its ends, the webs on each of the ends of said tiles being secured together, there being a duct forming space between said composition tile and said ceramic tile.

ARTHUR R. DIXON.
